UNITED STATES PATENT OFFICE.

GEORGE SAMUEL HOOKER, OF BRISBANE, QUEENSLAND, AUSTRALIA.

MATTRESS.

Application filed August 22, 1923, Serial No. 658,808, and in Australia September 18, 1922.

This invention relates to mattresses for use on beds, couches, and the like, the object being to so improve the construction thereof that the cost of manufacture is reduced, as, not only is less material required, but the cost of labour is reduced. The construction and arrangement are such that a mattress is made which is much more comfortable and which will retain its shape and condition for a greater length of time than is the case with other mattresses on the market.

In carrying out my invention I make the cover of ticking or other like material, but I dispense with the usual tufts and ties. In order to keep the kapok, horse-hair, fibre, or other stuffing material in its proper position and to make a more comfortable mattress, I provide partitions between the top and bottom covers. These partitions are arranged transversely and longitudinally, so that transverse, longitudinal, or rectangular compartments or cells are provided. As alternatives, the partitions may be arranged diagonally so that diagonal or diamond shaped compartments or cells are formed, or they may be arranged in the form of rectangles or ovals, one within another, or in the form of oval or rectangular spirals with or without sectional partitions dividing them into smaller sectional compartments or cells. The compartments or cells may be of any desired size.

The partitions are, as far as possible, secured to the top and bottom covers, but, in order to facilitate construction and filling, the stitching may be dispensed with at certain places.

The stuffing material is placed in the respective compartments or cells by machine or hand, as found most suitable.

In order that my invention may be better understood I will now describe it with the aid of the accompanying drawings, in which

Fig. 1 is a perspective view of part of a mattress (broken).

Fig. 2 is another perspective view of part of a mattress (broken).

Figs. 3-8 show alternative arrangements.

In carrying out my invention I make the cover A of the mattress of ticking or other

material, which is cut and formed in the usual way with the top and bottom A, ends B, and sides C. Partitions D, formed of strips of ticking, canvas, calico, or other material, are arranged transversely, longitudinally, diagonally, spirally (oval or rectangular), and sewn to the top and bottom A, ends B, and sides C, as the case may be. Supplementary partitions E, consisting of strips or short lengths, are placed between the partitions D as and where advisable so as to form the interior of the mattress into cells F, and sewn to the partitions D. I may, in some cases, sew these supplementary partitions E to the top and bottom covers but provision must be made for the purpose of filling. Furthermore, I may, in some cases, dispense with the supplementary partitions E, the compartments or cells F being, therefore, larger, but, owing to their formation and arrangement, they keep the stuffing in place.

The mattress is filled with the usual packing or stuffing, such as kapok, fibre, horse-hair, feathers, springs, or other suitable material, in the usual way, preferably by machine, the spout of which is passed into the mattress over the various supplementary partitions E and gradually withdrawn as it is filled. For such purpose, the ends B and sides C would be left unsewn at one or more places. The partitions D may also be left unsewn, where found necessary, for a similar purpose.

It will be seen, from the foregoing, that, in carrying my invention into effect, I form cells F within the mattress, in which the filling material or stuffing is placed. These cells F may be of any shape, and they may be made uniform in size or made smaller in the middle, as in the case of single and three-quarter mattresses, and, say, one quarter width from each side, as in the case of double mattresses.

Having now particularly described and ascertained the nature of my said invention and in what manner the same is to be performed, I declare that what I claim is:—

In a mattress, a cover including top, bottom and sides, parallel partitions arranged within the cover and extending from side to

side thereof in one direction and having the edges thereof secured to the top, bottom and certain of the sides of the cover to provide a plurality of non-communicating chambers and supplementary partitions arranged between the first mentioned partitions and subdividing the chambers into

a plurality of cells, the supplementary partitions being secured only at their ends to the first mentioned partitions whereby to 10 permit access to the several cells for the purpose of introducing filling material.

In testimony whereof I affix my signature.
GEORGE SAMUEL HOOKER.
